UNITED STATES PATENT OFFICE.

WILLIAM PORTER DREAPER, OF LONDON, ENGLAND.

PROCESS AND APPARATUS FOR THE MANUFACTURE OF ARTIFICIAL SILK OR THE LIKE.

Application filed January 14, 1922. Serial No. 529,348.

To all whom it may concern:

Be it known that I, WILLIAM PORTER DREAPER, a subject of the King of Great Britain, residing at London, England, have 5 invented a new and useful Improved Process and Apparatus for the Manufacture of Artificial Silk or the like (for which I have made application for patents as follows: in Great Britain, November 10, 1920, No. 10 31,854 of 1920, and Japan November 3, 1921, No. 74,120), of which the following is a specification.

This invention relates to the manufacture of artificial silk, and like artificial filaments or strands, more especially when such filaments or strands are to be converted into staple fibre by a process of the kind wherein in the filaments or strands are formed in a precipitating bath, as in the so-called viscose process, and wherein the solution of cellulose or a cellulose compound is forced through a jet into the precipitating bath and is then led out of the same and up over a godet wheel and then down through an open 20 guider tube into a centrifugal box which is set above the level of the bath, and the object of the present invention is to improve the ordinary practice of manufacture so that it is possible to manufacture both artificial silk 25 and staple fibre, economically by the centrifugal method of spinning. Also the strain to which the strands are subjected is materially reduced, and an excessive twisting of the fibre is avoided whereby a 30 fibre is obtained which, when cut into staple lengths, will have sufficient twist to prevent the strands from unravelling when spun into yarn, but not sufficient to interfere with carding of the fibre. A 35 further advantage in producing staple fibres in this manner is the production of fibres of uniform length which is impossible in the use of fibres cut from a mass of waste material in which the fibres are of various 40 lengths. Cloth woven from yarn made in this manner differs from that made from continuous uncut fibres in that it has a thicker warmer feel due to the enclosure of air between the loose ends, in this manner 45 simulating wool while at the same time having the lustre of silk. The production of fibre in staple lengths as herein set forth simplifies and cheapens the manufacture of such yarn as compared with the use of waste 50 which is difficult to card and spin.

According to the present invention, for

the purpose of obviating the rewinding of the strand in order to bring it into skein form, the strand of filaments is wound into a centrifugal box of sufficiently large diameter to form a skein directly, whereupon the convolutions are first secured at suitable intervals around the skein, for example, by cross lacing, and the skein then removed from the centrifugal box.

The strand during the time it is being wound in the centrifugal box, is preferably reciprocated rapidly along a line parallel to the axis of the box, so as to give a result similar to that known as cross reeling in ordinary skein winding. This is advantageously effected by making the guider tube for the strand or filament stationary and providing it at its lower end with an independently movable tubular extension which projects below the lower end of the main tube and has a vertical reciprocatory motion imparted to it in any suitable known manner. By this means, it is possible to collect in the box much larger quantities of filament than heretofore.

Moreover in order to facilitate starting of the spinning, means are provided for reducing the speed of drawing off the strand during the starting, the speed being accelerated after the spinning has been started. An advantageous method of effecting this consists in making the godet-wheel of conical form so that, without altering the speed at which this wheel is driven, the speed of drawing off can be varied by moving the godet wheel axially, for example the godet-wheel may be made in the form of a truncated cone having a cylindrical extension at each end.

In the accompanying drawings:—

Figure 1 is an elevation partly in vertical central section of a spinning plant suitable for carrying the present invention into practice, the godet wheel being looked at in the direction of its axis.

Figure 2 shows the godet wheel separately looking in a direction at right angles to that in Figure 1.

Figure 3 shows a skein ready for removal from the centrifugal box.

Referring to the drawings, the strand A from the precipitating bath passes through a suitably supported guider B to the godet wheel which is preferably set directly at the end of the bath instead of some way above it as in ordinary practice. The strand is

drawn over this by friction at the required rate and then falls directly into a centrifugal box which is suitably set under the guider. By working in this manner, the construction 5 of the spinning frame is simplified and the path of the strand is easily controlled and the filaments subjected to less friction.

The godet used may be of the ordinary 10 type, but it is preferred to use one of a construction where its surface is coneshaped. Then by varying the position of the cone the speed at which the strand is drawn off can be varied at will, for example, it may be slow 15 at first and accelerated after actual spinning has started.

This type of godet is illustrated in Figures 1 and 2, in which there is a conical part C having a cylindrical extension D at its smaller end and a cylindrical extension E 20 at its larger end. This godet slides axially on its driving shaft F and is prevented from turning relatively thereto by means of a feather or other suitable known means. The godet is provided with an extension 25 having an annular groove G in which runs a roller H mounted on a rod J whereby the godet can be brought into position to bring the strand on to the small cylindrical extension D so as to feed the strand forward 30 at a low speed for starting, or on to the large cylindrical extension so as to feed the strand forward at a higher speed for normal work. By this means the change from one speed to the other can be brought about gradually 35 by simply moving the cone sideways on its driving shaft. In cases where such an axially movable conical godet is not employed, it is necessary to correspondingly move the guider B placed before it in order to obtain 40 the same effect, but the former procedure is preferable. Again for convenience the godet may be mounted on its driving spindle by means of a suitable clutch so that the driving spindle can turn freely therein when the 45 attendant wishes to stop it temporarily for cleaning or other purposes.

The open guider tubes which introduce the strands into the centrifugal boxes may be mounted on a common cross bar which 50 is reciprocated vertically by cam mechanism so that the strands may be coiled equally on the centrifugal box.

I have however found it advantageous to work with a stationary open guider tube 55 and a non-reciprocating centrifugal box. This can be done by using a somewhat shorter fixed guider tube K (Figure 1) and fitting loosely over the lower end of this tube an outer and shorter tube L of suitable length. This outer tube is mounted on a bar M suitably moved up and down for example through links N, N so that it delivers the strand into the centrifugal box O 60 in a similar manner to the ordinary moving guider. Thus the open guider and centrifu-

gal box are kept in constant positions, and the necessary coiling of the strand in the box by the means indicated is secured. The movement of the outer tube is effected by cam mechanism and preferably a stream of 70 liquid is continually passed down the open guider K see Figure 1, and thus also through the outer tube L, which passes on the strand into the centrifugal box, as in the specification of my former application for Letters 75 Patent Serial No. 515378, November 15, 1921, see the jet P or P', Figure 1.

In order to eliminate the ordinary process of manufacture wherein the strand is first coiled into a cake and is then by a separate 80 process wound into skein form, a centrifugal box O of increased diameter is used in conjunction with a different treatment of the strand, which is then collected in loops or circles of such a diameter that these correspond in size to those present in ordinary practice. Thus there is not produced a cake of strand in a centrifugal box of about 85 5 inches diameter as in the ordinary practice, but a coil of strand in a centrifugal 90 box of for example 15 inches diameter. The larger centrifugal box is preferably supported on a table fixed directly to the driving shaft. Having collected a suitable amount of this strand in this special box, and having 95 made certain that the open guider is actuated in such a manner that, as the strand is coiled, it travels rapidly from side to side of the mass of coiled strand, a result is obtained which corresponds to what is known 100 as cross reeling in ordinary skein winding. The coil of strands is then carefully cross laced, in for example, three equidistant places as shown in Figure 3, before lifting it from the box, and in this way it is ensured 105 that the relative position of the strands remains fixed during subsequent operations. Alternatively, there is gently introduced, for example three suitable clips which pass in front of and behind the coil 110 at B' in Figure 3 so that the circle of wound or coiled strand is temporarily held in say three equidistant places while the coil is removed from the box. In this last case the coil is then cross laced near each of the clips 115 which coil then becomes a skein. The temporary clips are then removed. This method of working is especially useful where filaments are collected which are, in a final 120 operation of manufacture, cut up into short lengths to produce staple fibre. Under such conditions the twist given to the strand by the centrifugal process may be greatly reduced, for example to such a degree that it will not interfere with the subsequent 125 carding and other operations and is yet sufficient to prevent the cut lengths of strand from unravelling.

What I claim is:—

1. An apparatus for the manufacture of 130

artificial silk staple fibre and like artificial filaments, said apparatus comprising a godet wheel, a stationary guider tube having its upper end funnel shaped, a reciprocatory

5 guider below said guider tube, and a centrifugal box to receive the filaments from this reciprocatory guider.

2. An apparatus for the manufacture of artificial silk staple fibre and like artificial 10 filaments, said apparatus comprising a godet wheel, a stationary guider tube having its upper end funnel shaped, means for supplying liquid continuously to the interior of the stationary guider tube, a reciprocatory 15 guider below said guider tube, and a centrifugal box to receive the filaments from the reciprocatory guider.

3. A process for the manufacture of staple fibre from strands of artificial silk which 20 may be easily carded and spun, consisting in that the strand of filaments is wound into a centrifugal box of sufficiently large diameter to form a skein directly with a relatively low degree of twist, whereupon the convolutions are secured at intervals around the 25 skein, the skein removed from the centrifugal box, dried and cut off into short lengths to form staple fibre.

4. A process for the manufacture of artificial silk, staple fibre and like artificial filaments, consisting in that the strand of filaments is wound into a centrifugal box initially at a low rate of speed which is gradually increased to the normal rate of spinning 35 by moving the path of the strand, and a conical godet wheel having a cylindrical extension at each end relatively to each other, the centrifugal box being of sufficiently large 40 diameter to form a skein directly, whereupon the convolutions are secured at intervals around the skein, and the skein removed from the centrifugal box.

5. A process for the manufacture of staple fibre from strands of artificial silk and like artificial filaments which may be easily carded, consisting in that the strand of filaments passes over a godet wheel through a longitudinally reciprocating guider tube through which a current of liquid is continuously passed, the strand then passing 50 into a centrifugal box of sufficiently large diameter to form a skein directly, whereupon

the convolutions are secured at intervals around the skein, and the skein removed from the centrifugal box dried and cut into 55 short lengths to form staple fibre.

6. An apparatus for the manufacture of artificial silk, staple fibre and like artificial filaments, said apparatus comprising a godet wheel, a reciprocating lower guider tube, a 60 stationary upper guider tube, a funnel at the top of said upper guider tube, and a centrifugal box of sufficiently large diameter to form a skein directly.

7. An apparatus for the manufacture of 65 artificial silk, staple fibre and like artificial filaments, said apparatus comprising a godet-wheel, a reciprocating lower guider tube, an upper guider-tube, a funnel at the top of said upper guider tube, means for supplying liquid continuously to the interior of said funnel, and a centrifugal box of sufficiently large diameter to form a skein directly.

8. An apparatus for the manufacture of 75 artificial silk staple fibre and like artificial filaments, said apparatus comprising a godet-wheel made in the form of a truncated cone with a cylindrical extension at each end, means for moving said godet-wheel axially, a 80 reciprocating guider tube, means for supplying liquid to the interior of said guider-tube, and a centrifugal box of sufficiently large diameter to form a skein directly.

9. An apparatus for the manufacture of 85 artificial silk, staple fibre and like artificial filaments said apparatus comprising a godet wheel having a conical surface arranged with its upper surface in substantially the same horizontal plane as the exit end of the precipitating bath, means for moving said godet wheel axially, a reciprocating lower guider tube, an upper guider tube, a funnel at the top of said upper guider tube, means for supplying a current of liquid to the interior of 90 said funnel, and a centrifugal box of sufficiently large diameter to form a skein directly.

Dated this 31st day of December 1921.
